JEWELRY DISPLAY STAND

Italo Rotondo, Providence, R.I., assignor to Beatrix Jewelry Company, Providence, R.I., a corporation of Rhode Island

Filed Apr. 15, 1963, Ser. No. 74,431

Term of patent 7 years

(Cl. D80—9)

FIG. 2.

FIG. 1 is a perspective view of a jewelry display stand showing my new design, the broken line representation of bracelets being for purposes of illustration only; and

FIG. 2 is a top plan view thereof.

I claim:

The ornamental design for a jewelry display stand, substantially as shown and described.
